CLAIM

The ornamental design for a support arm for a display, as shown and described.

DESCRIPTION

In a preferred embodiment, the nature of this product is an adjustable support arm for a flat panel display for a computer.

FIG. 1 is a rear, right perspective view of a support arm for a display embodying our new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof; and,

FIG. 7 is a bottom plan view thereof.

The broken line representations of a display in FIGS. 1 and 3-7, of display mounting structure in FIGS. 1 and 3-7, of recessed side wall areas in FIGS. 1, 3 and 4, of hooks in FIGS. 1-4 and 7, of an adjustment dial in FIGS. 1, 3, 4, 5 and 6, and of a table in FIGS. 1 and 6, are for the purpose of illustration only, and form no part of the claimed design.
